(57) **CLAIM**

The ornamental design for a bottle, as shown and described.

DESCRIPTION

FIG. 1 is a front perspective view of a bottle of the present invention;

FIG. 2 is a left side view, the right side being a mirror image thereof;

FIG. 3 is a front side view, the back side being a mirror image thereof;

FIG. 4 is a top view thereof; and,

FIG. 5 is a bottom view thereof.

The broken lines illustrate portions of the bottle that form no part of the claimed design.

1 Claim, 4 Drawing Sheets(56)
